Primary Examiner — Elizabeth A. Albert(74) *Attorney, Agent, or Firm* — Quickpatents, LLC;
Kevin Prince(57) **CLAIM**

The ornamental design for a flower box, as shown and described.

DESCRIPTION

FIG. 1 is a perspective view of a flower box, showing my new design in a closed position;

FIG. 2 is a rear elevational view of FIG. 1;

FIG. 3 is a front elevational view of FIG. 1;

FIG. 4 is a left-side elevational view of FIG. 1, the right-side elevational view being a mirror image thereof;

FIG. 5 is a top plan view of FIG. 1;

FIG. 6 is a bottom plan view of FIG. 1;

FIG. 7 is a perspective view thereof, illustrated in a partially open position; and,

FIG. 8 is a top plan view thereof, illustrated in a flat, unfolded position.

The broken lines showing a seatbelt, car seat, and flowers in FIG. 1 depict environmental matter and form no part of the claimed design.
